METHOD FOR RUNNING A TUBULAR MEMBER IN A WELL

Gilbert H. Tausch, Houston, Tex., assignor, by mesne assignments, to Esso Research and Engineering Company, Elizabeth, N. J., a corporation of Delaware

Application October 20, 1954, Serial No. 463,493

9 Claims. (Cl. 166—27)

The present invention is directed to a method for running a tubular member in a well. More particularly, the invention is directed to positioning or retrieving a tubular member in a tubing arranged in a well casing. In its more specific aspects, the invention is directed to a method for drilling a well in which a tubing is arranged therein with its lower open end at a level substantially above a level from which production is to be obtained.

The present invention may be briefly described as a method for running a tubular member in a tubing having its lower open end arranged in a well casing at a level substantially above a level from which production is to be obtained. The method comprises inserting the tubular member in the tubing and causing the tubular member to travel freely in unrestricted relationship to the tubing or the wellhead downwardly in the tubing a predetermined distance. The tubular member is then restrained in the tubing after the travel and thereafter fluid may then be flowed through the tubing and tubular member either downwardly through the tubing and tubular member or upwardly through the tubular member and tubing. The tubular member may then be retrieved up the tubing by forcing the tubular member up the tubing for free travel therein.

The present invention also comprises a method for treating a well in which the tubing is arranged in a well casing with its lower open end at a level substantially above a level at which production is to be obtained. A tubular member is inserted in the tubing and released therein and caused to travel downwardly freely in the tubing in unrestricted relationship to the wellhead and tubing a predetermined distance or until at least a portion of the tubular member projects from the open end of the tubing to increase the effective length of the tubing. A treating reagent, such as fluid cement, a washing vehicle, such as water and the like, acid, and other materials with which wells are treated, may then be flowed downwardly through the tubing and tubular member into the casing and into the formation as desired. The treating reagent, such as fluid cement, may have pressure imposed thereon and excess fluid cement or treating reagent may be removed from the casing up the tubular member and tubing and thereafter the tubular member may be retrieved from the tubing by forcing same upwardly in the tubing by pressure imposed thereon through the casing annulus.

The present invention is particularly adaptable to cementing operations in which cement is employed to close off perforations in a well casing. The invention is peculiarly adaptable in the use of modified fluid cements of the nature described in the patent to Salathiel, U. S. 2,482,459. Other modified fluid cements having a low water loss may be used. Likewise, oil-emulsion cements or cement slurries in oil may be used in the practice of the present invention.

Treating reagents, such as acid and acid gels and the like, may be used.

The well and casing may be treated in accordance

2
with the present invention by use of washing liquid, such as fresh or salt water, or an aqueous medium to remove sand and the like from the well casing and the tubing.

5 The present invention is also adaptable to opening up formations by imposing pressure thereon through perforations in the casing or in the open hole by use of a liquid, such as crude oil, fractions thereof, acid gel and the like, which may contain a weighting agent and/or 10 propping agent, such as sand and the like by imposing pressure on the liquid used to open up the formation. The invention is also susceptible to extending the effective length of the tubing where the tubing is arranged in the well casing at a level a substantial distance above a 15 plurality of hydrocarbon productive intervals, zones, strata, formations and the like from which desirable hydrocarbons, such as gas and/or oil, are to be obtained. In the practice of the present invention the fluid, such as cement slurry, acid, washing vehicle, water and the like, may be flowed downwardly through the tubing and tubular member into the casing and excess treating agent may be removed from the casing by reversing same out by flowing a washing liquid down the annulus between the casing and the tubing and causing the treating reagent 20 to flow backwardly through the tubular member and the tubing.

A preferred mode of the present invention may be further illustrated by reference to the drawing in which:

Fig. 1 shows the insertion of the tubular member into the tubing;

Fig. 2 shows the tubular member arranged in the lower end of and projecting from the tubing;

Fig. 3 illustrates the use of the present invention in spotting a cement slurry in the casing; and

Fig. 4 shows the retrieving of the tubular member up the tubing.

Referring now to the drawing in which identical numerals will be employed to designate identical parts, numeral 11 designates a well bore drilled from the earth's surface 12 to penetrate a plurality of hydrocarbon productive intervals or formations 13, 14, and 15 which are separated by non-productive formations or intervals 16 and 17. The well casing 18 is arranged in the well bore 11 and is cemented in place with primary cement 19. A tubing 20 extends from above the surface of the earth 12 to above the hydrocarbon productive interval 13 with its lower open end 21 arranged above the interval 13. The tubing 20 is connected by a conduit 22 to a tubing pump 23 which, in turn, is connected by a conduit 24 to a source of treating fluid, such as a cement slurry. The annulus A between the casing 18 and the tubing 20 is provided with a conduit 25 which, in turn, connects to an annulus pump 26 which has a line or conduit 27 connected to a source of washing fluid, such as water or oil and the like. It is understood that pumps 23 and 26 may be the same pumps provided with different lines for connecting to the tubing 20 or to the annulus A as may be desired.

A lubricator 28 shown in more detail in Fig. 1 is attached to the tubing. This lubricator may be provided with a plurality of valves 29 and a blow-out preventer 29' for insertion of tools into the tubing while maintaining the well under pressure.

A tubular member 30 is shown in Fig. 1 being run into the tubing 20 through the lubricator 28, the tubular member 30 being made up of a plurality of sections 31 which may be screwed together by such as threaded collars 32 to provide a tubular member 30 of any desired length.

At least one end of the tubular member 30 may be closed by an expendable plug 33 which is attached to the tubular member 30 by shear pins 34. In Figs. 1 and 2, the plug 33 is shown closing the lower end of the tubular

member 30. The sections 31 are suspended in the lubricator and tubing prior to running by blow-out preventor 29'. As lengths or sections 31 of the tubular extension member 30 are added therein, the tubular member is gradually lowered into the tubing and restrained therein until the desired length of the tubular member has been made up. Thereafter the tubular member, as shown in Fig. 2, is released in the tubing 20 and caused to travel downwardly therein in unrestrained travel from the earth's surface and through the tubing. The tubular member 30 may gravitate downwardly in the tubing 30 or it may be forced downwardly therein by pumping fluid into the tubing 20 through conduit 22 from pump 23 and conduit 24 or by circulating fluid downwardly through the tubing. The rapidity of travel of the tubular extension member 30 may be controlled by circulating fluid introduced into the tubing through conduit 22 or conduit 25; thus by introducing fluid through conduit 25 the degree of travel downwardly in the tubing 20 of the extension member 30 may be restrained or stopped all together if desired.

In any event, in Fig. 2 the tubular extension member 30 with its lower end closed by a plug 33 held thereto by shear pin 34 is allowed to travel downwardly a predetermined distance in the tubing 20 and project from the open end 21 thereof to extend to the formation 15.

The tubular extension member 30 carries packing 36, such as chevron packing and the like, for engaging with the walls of a landing seat, supporting means, or landing nipple 38, such as has been described in the Composite Catalogue of Oil Field and Pipeline Equipment, 1952-53 ed., page 4064.

The tubular member 30 is provided with latching dogs 40 which secure or anchor the upper end of the tubular member 30 in the landing nipple 38, as shown.

After the tubular member 30 has been landed in the landing nipple 38, as shown, with its lower end extending to the interval 15 which previously had been perforated with a gun perforator and the like to form a plurality of perforations 42 and it is desired to treat the formation 15 through the perforations 42, the expendable plug 33 is blown from the tubular extension member 30. In these situations it may be desirable first to supply hydraulic pressure either to the tubing 20 or the annulus A to test the system to determine whether or not the upper end of the tubular member 30 is safely landed and secured in the landing nipple 38. After the pressure test has indicated the securing of the tubular member in the landing nipple 38 a predetermined amount of pressure is placed on the tubing and the tubular member 30 sufficient to shear shear pins or frangible means 34 and cause the plug 33 to be blown from the tubular member 30.

In Fig. 3, the plug 33 is shown resting on the bottom of the well with the tubular member 30 open. A treating fluid, such as cement, is then introduced by pump 23 through line 22 into the tubing 20 and caused to flow downwardly through the tubing 20 and tubular member 30 into the casing 18 adjacent the interval 15. This cement fills the perforations 42 and in the case of the modified cement, such as described in the patent to Salathiel supra, filter cakes or buttons 43 are formed in the perforations 42 to seal off the interval 15 from the well casing.

Thereafter the excess fluid cement or treating reagent may be removed from the well by circulating a wash liquid, such as water or oil, down the annulus A, the washing liquid being introduced into the annulus A by way of conduit 25 from a pump, such as 26. This causes the cement to be reversed outwardly through the tubular member 30 and the tubing 20 and then outwardly from tubing 20 by conduit 22.

When it is desired to reperforate the casing in an interval vertically displaced from the perforated interval 15 or in the interval 15 the tubular member 30 is retrieved from the tubing 20, as shown in Fig. 4. In this particular in-

stance, a retrieving tool, such as 50, as shown in Fig. 4, is placed in the lubricator 28 and forced downwardly through the tubing 20 by pump pressure from pump 23 and conduit 22. The retrieving tool 50 comprises a swab cup 51 or a suitable sealing means which serves as a piston to allow the retrieving tool 50 to be pumped down the tubing 20. The retrieving tool 50 has a prong 52 which fits into the open end of the tubular member 30 and closes same and is also provided with a plurality of releasing prongs 53 which releases the hold-down dogs 40, holding the upper end of the tubular member in the supporting means 38. Since the swab cup 51 provides a seal with the tubing 20, the tubular member may then be retrieved by applying pump pressure through pump 26 and conduit 25 on the annulus A which will force the tubular member 30 up the tubing 20 and allow same to be engaged by the blow-out preventer 29' for retrieving the sections 31 of the tubular member from the tubing.

Thereafter after the tubular member 30 has been retrieved from the tubing, a gun perforator either of a bullet or shaped charge type may be lowered and/or run in through the tubing adjacent the interval 15 to re-perforate same or adjacent one of the hydrocarbon productive intervals 13 or 14 as may be desired. After hydrocarbon production has been obtained again from a hydrocarbon productive interval, such as 13, 14 or 15, where it has been reperforated, the tubular member such as 30, may be again run into the tubing for cementing off or treating one of the hydrocarbon productive intervals as may be desired.

Although the invention has been discussed particularly with respect to running the tubular member 30 through the tubing to project therefrom, it is contemplated that the tubular means 30 may be run any predetermined distance within the tubing 20 as may be desired.

The present invention is very advantageous since heretofore tubular members, such as 30, have been run only on wire lines from the surface of the earth. The present invention allows the running in and retrieving of the tubular member without the use of workover rigs or pipe handling equipment or the use of wire lines. In the present invention the only equipment necessary is a pump for circulation of the apparatus down and up the tubing as has been described. While two pumps may be used, a single pump with the proper connections may be used to circulate fluid either down the tubing or down the annulus as may be desired. While the invention has been described and illustrated by closing in one end of the tubular member, it is possible to practice the present invention without closing the tubular member while running same into the well.

The present invention has been used in the field to perform a cementing operation in which the tubing was permanently arranged at a level substantially above the interval to be cemented. In this instance the tubing extension was suspended in the tubing as it was being inserted therein from a mandrel which latched in a collar recess and seals immediately below a landing nipple having a honed interior surface.

The tubing extension was run in and retrieved by circulation before and after cementing operations in the following manner: after the bottom of the tubing extension was sealed with an expendable plug, the tubing extension was allowed to float into position without the use of a wire line. Since the descent of the tubing extension assembly was accelerated as water in the well replaced the air in the tubing extension, reverse circulation, that is fluid was flowed upwardly in the tubing from the annulus and was employed to decelerate the assembly as it approached the landing nipple in the lower end of the tubing. When the assembly was seated, the tubing and tubing extension assembly were then pressure tested in burst and collapse. The expendable plug was then blown out of the tubing with approximately 1100 pounds pump pressure. Thereafter, the producing interval was plugged with modified cement as described supra, and excess

cement circulated out. A retrieving assembly composed of a fishing head, rubber swab cups, a pulling tool, and a releasing prong was then circulated down the tubing into position as has been described supra. A latching assembly was also mounted on the well head. Fluid was then circulated down the annulus between the casing and tubing (reverse circulation) forcing the tubing extension back up the tubing. The tubing assembly and the retrieving assembly were successfully retrieved and caught at the well head using approximately 390 pounds pump pressure for reverse circulation.

As mentioned before, the rate of descent of the tubular member may be controlled, such as increased or decreased, by circulating fluid up or down the tubing with the surface pump.

Many modifications of the present invention in well completion may be practiced without departing from the spirit and scope thereof.

The nature and objects of the present invention having been completely described and illustrated, what I wish to claim as new and useful and secure by Letters Patent is:

1. A method for treating a well in which a tubing is permanently arranged in a well casing with its lower open end at a level substantially above a level from which production is to be obtained, said tubing being provided with a lubricator, which comprises making up and inserting a tubular extension member in the upper end of said tubing through said lubricator, said tubular member having a passageway therethrough, suspending said tubular member in the upper end of said tubing, then releasing said tubular member for travel by gravity downwardly in said tubing, controlling the rate of downward travel of said tubular member by circulating fluid down the casing-tubing annulus and up said tubing against the released tubular member until said tubular member seats in and projects from the lower open end of the tubing to increase the effective length of the tubing, maintaining said projecting tubular member in the lower end of the tubing and flowing a treating fluid downwardly through and out of said tubing and tubular member, and then forcing said tubular member up the tubing for travel therein by circulating fluid down the casing-tubing annulus and up the tubing and against said tubular member.

2. A method in accordance with claim 1 in which the passageway through the tubular member is closed after flowing said treating fluid and prior to forcing the tubular member up the tubing.

3. A method in accordance with claim 1 in which the passageway through the tubular member is closed prior to inserting the tubular member into the tubing through the lubricator and the passageway through the tubular member is opened after the tubular member has increased the effective length of the tubing for flowing said treating fluid therethrough.

4. A method in accordance with claim 3 in which the passageway through the tubular member is closed after flowing said treating fluid and prior to forcing the tubular member up the tubing.
5. A method in accordance with claim 1 in which the fluid is a cement slurry.
6. A method in accordance with claim 1 in which the fluid is a washing vehicle.
7. A method in accordance with claim 1 in which the fluid is water.
8. A method in accordance with claim 1 in which the fluid is acid.
9. A method for treating a well in which a tubing is permanently arranged in a well casing with its lower open end at a level substantially above a level from which production is to be obtained, said tubing being provided with a lubricator, which comprises making up and inserting a tubular extension member in the upper end of said tubing through said lubricator, said tubular member having a passageway therethrough, suspending said tubular member in the upper end of said tubing, then releasing said tubular member in said tubing for travel by gravity downwardly in said tubing, controlling the rate of downward travel of said tubular member by circulating fluid down the casing-tubing annulus and up said tubing against the released tubular member until said tubular member seats in and projects from the lower open end of the tubing to increase the effective length of the tubing, maintaining said projecting tubular member in the lower end of the tubing and flowing fluid cement downwardly through and out of said tubing and tubular member into said casing, applying pressure to the cement in the casing, flowing a fluid down the casing-tubing annulus into contact with the fluid cement and thereby removing excess fluid cement from the casing up the tubular member and tubing, closing the passageway through said tubular member, and then forcing said tubular member up the tubing for free travel therein by again circulating fluid down the casing-tubing annulus and up the tubing and against the closed tubular member.
